UNITED STATES PATENT OFFICE.

GOTTHOLD EMANUEL KALTMAYER, OF SAN BUENAVENTURA, CALIFORNIA.

SEED-SOWER.

SPECIFICATION forming part of Letters Patent No. 319,586, dated June 9, 1885.

Application filed January 5, 1885. (No model.)

To all whom it may concern:

Be it known that I, GOTTHOLD E. KALTMAYER, of San Buenaventura, county of Ventura, and State of California, have invented 5 an Improvement in Seed-Sowers; and I hereby declare the following to be a full, clear, and exact description thereof.

My invention relates to that class of seed-sowers in which a box provided with adjustable discharges and rotating agitators is adapted to be mounted upon and used in connection with a revolving harrow, pulverizer, or plow; and my invention consists in novel details of construction and arrangement relating to the 15 means for adjusting the capacity of the discharges, the agitators by which the discharge is facilitated, the means for rotating the agitators, the manner in which the seed-box is mounted, and the adjustable discharge-spouts 20 by which the seed may be deposited in front of the harrow, pulverizer, or plow, or behind it in the furrow, all of which I shall herein-after fully explain.

The object of my invention is to provide a 25 simple, economical, and effective seed-sower.

Referring to the accompanying drawings, Figure 1 is a perspective view of my seed-sower. Fig. 2 is a transverse section. Fig. 3 is an enlarged section of the seed-box. Fig. 30 4 is a transverse section of the agitator.

A is an axle of any suitable running-gear, though more especially intended as an axle of a rotary harrow, B, such as is here represented, or any rotary pulverizer or plow. The end of 35 this axle is provided with a crank, a.

C is a bar or platform above the harrow, and having on its end a projecting pin, c.

D is the seed-box, the bottom of which is made of two thicknesses, spaced or separated, 40 and having openings or slots d made through them. Between the thicknesses of the bottom and inclosed thereby is the slide gate or bar E, having throughout its length the openings or slots e, which, by reason of the sliding motion 45 imparted to the gate-bar, are adapted to coincide wholly or in part with the openings d in the bottom of the seed-box. By means of this gate-bar the quantity of seed which is allowed to pass through the bottom of the seed-box is 50 regulated as may be desired. The sliding motion is imparted to the gate-bar by the following means:

Pivoted in a bracket, F, at the end of the box is a segmental gear, G, provided with a lever, g, which passes up through the slotted 55 bar H. This bar is graduated to a suitable scale, whereby the motion of the lever may be accurately determined. The segmental gear meshes with the short rack e' on the end of the gate-bar. Thus by means of the gear and 60 rack, the lever, and graduated bar, the movement of the gate-bar is determined, so that it is enabled to regulate the feed to a known or set quantity. The box D is supported above the platform by means of the brackets I, which hold it in a raised position, thereby enabling 65 the spouts J to lie at a suitable inclination between the bottom of the box and the platform. These spouts are adapted to receive the seed from the discharge-openings in the bottom of the box, and to carry it to one side of the platform, where it is discharged upon the ground. In some cases it may be desirable 70 that this discharge shall be made in front of the harrow, while in others that it shall be 75 made behind the harrow, into the furrow. In order to accomplish this the spouts are secured to the bottom of the box by means of nuts and bolts. (Represented by K.) By removing the nuts the spouts can be readily slipped off 80 the bolts and reversed, being fitted upon bolts upon the opposite side of the box, whereby 85 their direction of discharge is reversed.

Mounted longitudinally in the box is a shaft, L, upon which are mounted the agitators M. These consist of disks having upon their periphery the radial flanges m, which are preferably of a T shape, whereby they are adapted the better to move over or cover the entire length of the openings in the bottom of 90 the box. The agitators are fitted upon the shaft by means of perforated hubs, which are set by screws n, whereby they may be adjusted laterally to cause them to operate over each of the discharge-openings of the feed-box with 95 perfect accuracy. The end of shaft L is provided with a crank, l.

O is a rod or bar, the upper end of which is connected with the crank l, while the lower end is connected with the crank a of the running gear or harrow below. The center of this bar is slotted upon the pin c, extending from the end of the platform C. By means of this 100 connection the agitators are given an entire

revolution, and the direction of this revolution is the reverse of the direction of revolution of the running-gear.

The operation of the device is as follows: 5 The seed is placed in the box, which is suitably covered and the gate-bar is adjusted so as to regulate the capacity of the discharge-openings as desired, and the spouts are set in a proper position either to discharge in front 10 of or behind the harrow. As the machine is drawn forward, motion is transmitted from the axle A through the cranks a and l and bar O, to the agitators M, whereby they are given a complete revolution, for the purpose of continuously and certainly forcing the grain or 15 seed through the discharge-openings. The seed drops upon the spouts, and by them is discharged upon the ground.

Having thus described my invention, what I 20 claim as new, and desire to secure by Letters Patent, is—

1. In a seed-sower, the box D, having bottom openings or slots, d, in combination with the sliding gate-bar E, having openings or 25 slits e, and mounted under the box, as described, and the mechanism by which said gate-bar is reciprocated to make its openings coincide partially or wholly with the openings d, whereby the capacity of the latter is 30 regulated, consisting of the segmental gear G, pivoted on the end of the box, the rack e' on the end of the gate-bar, and the lever g, by which the segmental gear is operated, substantially as herein described.

2. In a seed-sower, the box D, having bottom openings or slots, d, in combination with the sliding gate-bar E, having openings or 35 slits e, whereby the quantity of the discharge is regulated, the pivoted segmental lever-gear 40 G and rack e', by which the gate-bar is operated, and the graduated slotted bar H, through which the lever of the segmental gear plays, and by which the amount of discharge is determined, substantially as herein described.

3. In a seed-sower, the box D, having bottom openings or slots, d, in combination with the rotating agitators M, within the box, said agitators having T-shaped radial flanges m, bolted through their periphery, substantially 50 as and for the purpose herein described.

4. In a seed-sower, the box D, mounted on suitable running-gear and having bottom open-

ings or slots, d, in combination with the shaft L, extending longitudinally through the box, and having an end crank, l, the agitators M, 55 mounted on the shaft and provided with T-shaped radial flanges, and the means by which a complete rotary motion in a direction the reverse of that of the running-gear is imparted to the agitators, consisting of the bar O, joining the crank of the agitator-shaft with a crank on the axle-shaft or wheel of the running-gear, and slotted on an intermediate fixed pin attached to the bar C, substantially as herein described. 65

5. The shaft or axle A of a rotary harrow, plow, or pulverizer having an end crank, a, and the bar or platform C, carried by said shaft, in combination with the seed-box D, having discharge-openings and mounted above and carried by the bar or platform, the agitators M, with T-shaped flanges, in the box, the shaft L, on which they are mounted, having an end crank, l, the pin e, projecting from the bar or platform, and the bar O, joining the cranks a 75 l and slotted on the pin e, all arranged and adapted to operate substantially as and for the purpose herein described. 70

6. In a seed-sower, the box D, having bottom openings or slots, d, in combination with the spouts J, under the box, adapted to receive and conduct the seed, said spouts being secured to the box by bolts and nuts K, whereby they may be reversed and be attached to the opposite side of the box, substantially as 85 and for the purpose herein described.

7. The rotary harrow B and the platform or bar C, carried by it, in combination with the seed-box D, having bottom openings, d, the brackets I, by which the box is secured upon 90 and raised above the platform, the reversible spouts J, under the box, between it and the platform, the sliding slotted gate-bar E, by which the discharge is regulated, and the rotating agitators M, within the box, all arranged to operate substantially as herein described. 95

In witness whereof I have hereunto set my hand.

GOTTHOLD EMANUEL KALTMAYER.
